UNITED STATES PATENT OFFICE

RUBY P. STINE, OF SHELBYVILLE, INDIANA

SNATH

Application filed January 17, 1931. Serial No. 509,354.

My invention relates to a means for securing a scythe to a snath.

For fastening a scythe to its associated snath the scythe is usually provided with a tang in the form of an arm integral with that end of the scythe which is to be attached to the snath, and extending in the same direction as does the cutting edge of the blade at substantially a right angle to the back of the blade. The free end of the tang is usually bent over to form a lug for co-operating with a depression or hole in a face plate secured to the snath-butt.

The face plate is usually a flat plate secured to a flattened portion of the butt of the snath on one side thereof. The tang of the scythe lies flat against this plate with the lug at its free end projecting through the opening provided in the plate, and is clamped in position against the blade by some suitable means. Such a device is shown in Patent No. 1,589,354 issued June 22, 1926 to John W. Boren.

Since the tang of the scythe is usually very nearly co-planar with the scythe blade, and since when it is attached to the snath the tang is substantially parallel with the lower portion of the snath; the blade is very nearly co-planar with this lower portion of the snath.

When such a scythe is in use, it is necessary for the snath to be held at a rather small angle to the ground in order that the cutting edge of the scythe may be more nearly perpendicular to the stalks of grass or other material being cut.

It is the object of my invention to provide a fastening means for securing a scythe to a snath in a position in which the scythe blade lies in a plane at a considerable angle to the butt of the snath, so that the snath may be held more upright in operation while still permitting a nearly perpendicular relation between the blade of the scythe and the material being cut.

To this end, I employ a face plate similar to that shown in the Boren Patent No. 1,589,354, but I dispose the tang-supporting portion of the plate in a tilted relation to the butt of the snath rather than parallel therewith.

When a scythe having a substantially co-planar blade and tang is secured by the tang to my tilted face plate, the tang of the blade is held at a considerable angle to the butt end of the snath, and the blade being substantially co-planar with the tang is also disposed in a tilted position with respect to the snath; and in use the snath may be held in a relatively upright position while still maintaining a nearly perpendicular relation between the scythe blade and the material which is being cut.

The accompanying drawing illustrates my invention: Fig. 1 is a side elevation of the butt end of the snath, the fastening means of which embodies my invention; Fig. 2 is a plan of the same snath-butt; Fig. 3 is a section through the clamping ring on the line 3-3 of Fig. 1; and Fig. 4 is a perspective view of the snath-butt with the face plate in position.

As in the device disclosed in the Boren Patent No. 1,589,354, the snath-butt 10 is provided with flat portions on the opposite faces. On that flat portion on the upper side of the snath-butt there is a clamping bolt-receiving plate 11 provided with a groove 12 extending longitudinally thereof, and held in place as by two rivets 13 and 14 extending through the snath-butt 10.

In order to provide a face plate whose face is tilted with respect to the snath-butt, I employ a plate which is offset at that end which is adapted to lie away from the end of the snath-butt, and which comprises a flat portion 20, and a wall 21 which extends from the upper end of the flat portion 20 toward the snath-butt and is provided at its edge which lies against the snath-butt with a flange 22. The face-plate is desirably secured to the snath-butt by means of the rivets 13 and 14 which also hold the bolt receiving plate 11 in place.

The wall 21 may be of any desired height, and upon its height depends the angular relation between the tang of the scythe blade and the snath-butt; and consequently the angle at which the scythe blade is out of co-planar relation with the snath-butt. Thus, the greater the height of the wall 21 the more

nearly upright the snath may be held while still maintaining a substantially perpendicular relation between the scythe blade and the material which is being cut.

5 I desirably close the sides of the face plate between the flat portion 20 and the wall 21 by walls 28 extending from the lateral edges of the flat portion to the snath-butt and integral with both the flat portion 20 and the 10 wall 21.

To brace the face plate 20 against stresses which tend to rotate it with respect to the snath-butt, the end of the plate 20 which is adjacent the end of the snath-butt is provided 15 with a down-turned finger 23 at the side thereof which will lie toward the scythe blade when such scythe blade is in position; and the flange 22 is provided with a similar down-turned finger 24 at the opposite side of the 20 face plate. These fingers extend circumferentially of and lie against the snath-butt 10.

In order that the tang of the scythe may be securely held in position on the flat portion 20 of the face plate, the portion 20 is provided 25 near its end which lies adjacent the end of the snath-butt with a lug 25; and near its opposite end with one or more holes 26 for the reception of a lug 27 on the tang. The tang 30 of the scythe is in the form of a tapering arm, and at the smaller end, which is the free end thereof, is provided the lug 27 which is adapted to be received by the hole 26 as noted above. Desirably, there is more than one hole 26 to provide for the adjustment 30 of the scythe in a plurality of positions; and when this is so the lug 25 desirably has its face 31 convexly curved in order that it may fully support the tang 30 in any of its positions of adjustment.

45 For securing the tang 30 against the flat portion 20 of the face plate, I desirably employ a ring 32 which has a set screw 33 whose end is adapted to be received in the groove 12 of the plate 11. The ring 32 is desirably large enough to provide considerable looseness of the ring on the snath-butt; in order that the ring may be free to move transversely of the snath-butt 10 and bear against the tang 30 at both of its lateral edges; and 50 also be free to move longitudinally of the snath-butt 10 to provide easy removal of the tang and scythe from engagement with the snath. Further, the large ring provides for variations in the thickness and width of 55 tangs, and also for different angular positions of the ring so that it may fully and firmly engage a tang in any of the different angular positions such tang may take by having its lug 27 received in different ones 60 of the holes 26 in the flat portion 20 of the tang receiving plate. It is to be noted that the lug 25 extends from the flat portion 20 of the face plate a distance less than the thickness of the tang 30 and accordingly does 65 not interfere with the full contact between

the ring 32 and the tang 30 along the edge of the tang 30 which is adjacent the lug 25.

When it is desired to assemble the scythe and the snath, the ring 32 with its set screw 33 withdrawn is slipped over the tang 30, and the ring and tang are together brought into association with the snath-butt 10. The lug 27 of the tang is inserted in one of the holes 26 in the flat portion 20 of the face plate, the ring 32 is slid toward the end of the snath-butt as far as the scythe permits, and the set screw 33 is screwed inwardly against the plate 11 to clamp the tang 30 in place.

70 The tang being thus clamped in place, the scythe which is integral with the tang 30 is securely held, for the ring bears against the tang 30 at both of its lateral edges and holds the tang firmly against the flat portion 20 of the face plate with the lug 27 on the tang extending into one of the holes 26, and with the back of the tang firmly braced against the face 31 of the lug 25. The scythe is then immovable with respect to the snath-butt 10 and is held in a position at a considerable angle out of co-planar relation with the 85 snath-butt.

80 It is to be noted that the tilted relation of the flat portion 20 of the face plate to the bolt-receiving plate 11 prevents any possible movement of the ring 32 away from the end of the snath-butt, and the shape of the tang and its associated scythe prevents any movement of the ring 32 toward the end of the 90 snath-butt.

95 This provision of a tilted tang receiving portion 20 on a tang-receiving plate carried by a flattened portion of the snath secures a 100 tilted relation of the scythe blade with respect to the snath without materially reducing the strength of the snath fastening; as would result were the snath-butt cut off at an angle to provide the tilted tang receiving plate, or if the tang was unduly bent out of the plane of the scythe blade to provide such 105 tilted relationship.

110 I claim as my invention:

115 1. In a snath fastening for detachably fastening to a snath the usual scythe-blade tang, a plate secured to the side of the snath at its scythe-receiving end and having a tang-receiving portion inclined away from said side of the snath, said tang-receiving portion being adjacent said side at the extreme end of said snath, supporting means 120 adapted to hold the upper end of said portion a considerable distance from said side of the snath and to support said portion throughout substantially its entire length, and means acting against the side opposite said blade-receiving scythe adapted to engage the exposed face of a tang and clamp said tang, blade, and snath together.

125 2. In a snath fastening for detachably fastening to a snath the usual scythe-blade tang, a plate secured to the side of the snath at its 130

scythe-receiving end and having a tang-receiving portion inclined away from said side of the snath, said tang-receiving portion being adjacent said side at the extreme end of said snath, supporting means adapted to hold the upper end of said portion a considerable distance from said side of the snath and to support said portion throughout substantially its entire length, said side being substantially parallel with the axis of said scythe receiving end of said snath, and means acting against the side opposite said plate receiving side adapted to engage the exposed face of a tang and clamp said tang, plate and snath together.

3. In a snath fastening for detachably fastening to a snath the usual scythe-blade tang, the combination of a plate secured to the side of the snath at its scythe-receiving end having a tang-receiving portion inclined away from said side of the snath, said tang-receiving portion being adjacent said side of the snath at the lower end thereof and the upper end of said portion being supported a considerable distance from said side of the snath, and a clamping ring of substantially larger diameter than said scythe-receiving end encircling said snath and said plate and having a set screw for co-operating with the side of said snath opposite to the plate receiving side to clamp the scythe-blade tang, said plate, and said snath together.

4. In a snath fastening for detachably fastening to a snath the usual scythe-blade tang having an upturned lug at its free end, a plate member secured to the side of the snath at its blade-receiving end comprising a flat tang-receiving portion, an end wall integral with the end thereof which lies away from the snath-end and having an integral flange which lies against said snath and by which said plate member is secured to said snath, and side walls integral with said end wall and said tang-receiving portion extending to the side of said snath, said tang-receiving portion being provided near said end-wall with an opening for receiving said tang-lug and near its other end with an abutment for engaging said tang on the side opposite to that from which the scythe blade projects.

5. In a snath fastening for detachably fastening to a snath the usual scythe-blade tang, a plate member secured to the side of the snath at its blade-receiving end comprising a flat tang-receiving portion, an end wall integral with the end thereof which lies away from the snath-end and having an integral flange which lies against said snath and by which said plate member is secured to said snath.

6. In a snath fastening for detachably fastening to a snath the usual scythe-blade tang having an upturned lug at its free end, a plate member secured to the side of the snath at its

blade-receiving end comprising a flat tang-receiving portion, an end wall integral with the end thereof which lies away from the snath-end and having an integral flange which lies against said snath and by which said plate member is secured to said snath, said tang-receiving portion being provided near said end-wall with an opening for receiving said tang-lug and near its other end with an abutment for engaging said tang on the side opposite to that from which the scythe blade projects.

7. In a scythe fastening for detachably fastening to a snath the usual scythe-blade tang, the combination of flattened portions on opposite sides of the snath at the scythe receiving end thereof, a set-screw engaging plate on one of said flattened sides, and a tang supporting member secured to the snath on the other flattened side and including a flat portion tilted with respect to the axis of the snath and against which said tang is adapted to lie and means including a set screw adapted to engage said plate for clamping said parts together.

8. In a snath fastening for detachably fastening to a snath the usual scythe-blade tang, a plate member secured against the bottom side of the snath body at its blade-receiving end and having a flat tang receiving face tilted with respect to the snath body, the end of said face which overlies the extreme end of the snath body being nearer to such snath body than the other end of said face, there being one or more supporting walls extending from said tang-receiving face and abutting said snath-body.

9. In a snath fastening for detachably fastening to a snath the usual scythe-blade tang, a plate member secured against the bottom side of the snath body at its blade-receiving end and having a flat tang-receiving face tilted with respect to the snath body, the end of said face which overlies the extreme end of the snath body being nearer to such snath body than the other end of said face, there being one or more supporting walls extending from said tang-receiving face and abutting said snath-body, a ring encircling said snath-end, and means acting between said ring and the side of the snath opposite said plate member to clamp the scythe-blade tang, said plate, and said snath-body together.

10. In a snath fastening for detachably fastening to a snath the usual scythe-blade tang, the combination with the body portion of the snath of a generally wedge-shaped plate fastened rigidly against the bottom side of the body portion with its thin edge toward the lower end of such body portion, and means for fastening the scythe-blade tang against the exposed flat surface of said wedge-shaped member so that the plane of the tang will be tilted with respect to the axis of said body portion.

11. In a snath fastening for detachably fastening to a snath the usual scythe-blade tang, the combination with the bottom side of the snath body of means for supporting the tang in tilted position with its free end considerably farther from the snath body than its end which joins the scythe-blade, said means including a wedge-shaped member interposed between said side of the snath and said tang and means acting against the side of the snath body opposite to the tang supporting means adapted to engage the exposed surface of the tang and clamp the tang, tang-supporting means, and snath body together.
12. In a scythe fastening for detachably fastening to a snath the usual scythe blade tang, a tang-receiving member adapted to present a tang-receiving face tilted with respect to the snath body and closer thereto at the end of such face which overlies the extreme end of the snath body than at the other end, and a wedge-shaped support for said member adapted to transmit to the underlying surface of the snath body forces acting against said tang receiving face.
13. In a scythe fastening for detachably fastening to a snath the usual scythe blade tang, a tang-receiving member adapted to present a tang-receiving face tilted with respect to the snath body and closer thereto at the end of such face which overlies the extreme end of the snath body than at the other end, a generally wedge-shaped support for said member adapted to transmit to the underlying surface of the snath body forces acting against said tang receiving face, and means reacting against the opposite side of the snath body for pressing a tank against said tang-receiving face.
14. In a scythe fastening for detachably fastening to a snath the usual scythe blade tang, a flattened portion on the side of the snath body, a tang-receiving member on said flattened portion and having a tang-receiving face tilted with respect to the snath body, the end of such face which overlies the extreme end of the snath body being closer to the snath body than the other end, and thrust transmitting means acting against said flattened portion and adapted to support said tang-receiving face throughout substantially its entire length.

In witness whereof, I have hereunto set my hand at Indianapolis, Indiana, this 14th day of January, A. D. one thousand nine hundred and thirty-one.

RUBY P. STINE.
